UNITED STATES PATENT OFFICE.

JOHN B. OLSON, OF FORT ATKINSON, WISCONSIN.

COLLAPSIBLE PERCH FOR POULTRY NESTS.

Application filed May 14, 1923. Serial No. 638,865.

My invention relates to improvements in collapsible perches for poultry nests.

The object of this invention is to provide improved means for preventing chickens 5 from entering the nests at night.

More particularly stated it is the object of this invention to provide means whereby an attendant may by a single movement of the hand or arm adjust a series of perches to a 10 position of non-use along a nesting cabinet having one or more tiers of nests, and whereby said perches when so adjusted will be held by gravity in such position until manually restored by the attendant to a position 15 for use.

In the drawing:—

Figure 1 is a perspective view of a nesting cabinet having two tiers of nests provided with perches embodying my invention.

20 Figure 2 is an end view of the same showing the perches in their raised position and with dotted lines indicating the position of use.

Like parts are identified by the same reference characters in both views.

The cabinet 1 may be of any ordinary type adapted to be connected with a supporting wall or held in a raised position by any suitable means. It is preferably provided with 30 a sloping roof 2 to prevent fowls from roosting thereon. The interior is suitably subdivided into nests each having an opening 3 through which the fowls may enter. It is not deemed necessary to illustrate the partitions which subdivide the nests, since the interior structure of the cabinet forms no part 35 of this invention.

A lower perch having a set of perch bars 5 and 6 is supported from the cabinet walls 40 by arms 7 pivoted to the wall brackets 8. The pivotal axis 9 is located at a substantial distance in front of the cabinet 1, whereby when the arms 7 are swung upwardly, their upper ends and also the perch bars 5 and 6 45 will be carried across a vertical plane through the pivot axis, the upper perch bar 5 resting against the front wall of the cabinet as is clearly shown in Fig. 2.

The upper perch 11 is similarly supported 50 by pivoted arms 12 from the wall brackets 13. Chains 14 normally support the perch 11 and the arms 12 in a horizontal position, said chains being connected with the cabinet at 15 above the brackets 13.

55 The arms 12 are connected to the arms 7 of the lower perches by links 17, whereby,

when the arms 12 are in a horizontal position, the arms 7 will be held by the links 17 also in a horizontal position. But by lifting pressure exerted upon either of the perches 60 5 or 6 or upon either of the arms 7, these perches may be raised to the position in which they are shown in Fig. 2 and while they are being so raised their motion will be transmitted to the arms 12 and perch 11 65 through the links 17. It will also be observed that the arrangement is such that the lower perches will support the upper ones when in the raised position, even though the upper perch or perches may not be carried 70 across a vertical plane through their respective axes. This is not only due to the fact that the lower perch or set of perches, in the construction illustrated, is of greater weight 75 and the swinging arms 7 of greater length than the upper perch, but it is also due to the fact that in raising the perches the lower ends of the links 17 swing past a vertical plane through the pivotal axis 9 and, therefore, the weight of the upper perch, when in 80 an outwardly inclined position, is exerted to press the lower perches supporting arm 7 more firmly against the cabinet at their upper ends. This result is facilitated by making the brackets 8 longer than the brackets 85 13 or at least by locating the pivotal connections 9 at a greater distance from the cabinet than the pivot pins 19 connecting the arms 12 with the brackets 13. While I have 90 illustrated a nesting cabinet having but two superposed tiers of nests and two perches at differing levels associated with the respective tiers of nests, it will be understood that the number of perches connected by the links 17 is not material. The number will 95 correspond in each case with the number of tiers of nests.

The perch supporting arms are of such length that when the perches are raised one perch bar of each perch will extend across 100 the associated apertures, thereby barring ingress and egress therethrough. When raised, however, the perch bars will be so close to the wall of the cabinet that there will be substantially no opportunity for 105 fowls to perch thereon, even though the apertures be sufficiently open to otherwise allow a fowl to enter. It will also be observed that the cabinet may be of any height, but the attendant will not be required to 110 reach the upper perch bar or bars. He can adjust the perches either to the position of

use or non-use by grasping the perch bar most convenient to his reach.

It will be observed that the link connections, with the upper and lower sets of bars respectively, are at differing distances from the cabinet, but at the same distances from the pivots about which the respective bars swing. Therefore, the perches can be raised to the folded position without requiring any sliding movement of the links on their pivotal connections.

I claim:

1. In a device of the character described, the combination with vertically spaced supports, of perch supporting arms each pivoted to one of said supports, and a link connecting the arms, the arc of movement of one of the arms about its pivot being so related to the arc of movement of the other of the arms about its pivot whereby to permit one of the arms to move across the plane of the link before the other of said arms moves to said plane.

2. The combination with a nesting cabinet having superposed nests, and associated perches adapted to facilitate access to the nests, each of said perches having arms pivotally supported by the cabinet, links connecting the perches, and means for holding the perch supporting arms normally in a horizontal position, said arms and perches being adapted for an upwardly swinging movement to a position of non-use with the supporting arms of one of the perches inclined upwardly and inwardly against the wall of the cabinet and with the supporting arms of the other of the perches inclined upwardly and outwardly from the wall of the cabinet.

3. The combination with a nesting cabinet having apertures at different levels affording access to the nests, of sets of perch-supporting brackets associated with the apertured portions of the cabinet, perch supporting arms pivoted to said brackets in front of said cabinet, perches mounted on said supporting arms and adapted to swing upwardly to positions across the associated apertures, links connecting the upper and lower perch-supporting arms, and supporting means for limiting the downwardly swinging movement of said arms, said pivotal con-

nections of the supporting arms being so located with reference to the cabinet as to allow one of said arms to swing across the vertical plane of their pivotal axes to an inclined position against the wall of the cabinet.

4. The combination with a nesting cabinet having apertures at different levels affording access to the nests, of sets of perch-supporting brackets associated with the apertured portions of the cabinet, perch-supporting arms pivoted to said brackets in front of the cabinet, perches mounted on said supporting arms and adapted to swing upwardly to positions across the associated apertures, links connecting the upper and lower perch-supporting arms, and chains connecting some of said arms with the cabinet and adapted to limit their downwardly swinging movement, said pivotal connections of the supporting arms being so located with reference to the cabinet as to allow one set of arms to swing across the vertical plane of their pivotal axes to an inclined position against the wall of the cabinet.

5. The combination with a nesting cabinet, of brackets secured to the cabinet sets of perch supporting arms having their inner ends pivotally secured to the cabinet brackets at different levels and in spaced relation to the cabinet, perch bars connecting the arms of the respective sets at differing distances from the cabinet, and links connecting the arms of said sets at the same distance from their respective pivotal connections.

6. In a device of the character described, the combination with supports, of perch-carrying arms pivoted to said supports at differing levels, a perch supported from the arms at each level, and a link connecting the arms supported at different levels, the fulcrum points of one of the arms to which said link is connected being so disposed with reference to said link that said arm will move pivotally across the plane of said link toward a position for contact with said support before the other arm to which said link is connected moves pivotally to its extreme position.

JOHN B. OLSON.
